UNITED STATES PATENT OFFICE.

EUGENE J. McCARTY, OF CLINTON, MASSACHUSETTS, ASSIGNOR TO MAX MACHINE COMPANY, OF CLINTON, MASSACHUSETTS, A CORPORATION OF MASSACHUSETTS.

BOILER-PLUG.

1,101,084.

Specification of Letters Patent. Patented June 23, 1914.

Application filed April 3, 1911. Serial No. 618,525.

To all whom it may concern:

Be it known that I, EUGENE J. McCARTY, a citizen of the United States, residing at Clinton, in the county of Worcester and 5 State of Massachusetts, have invented new and useful Improvements in Boiler-Plugs, of which the following is a specification.

My invention relates to boiler plugs, and its objects are to provide an effective means 10 of closure for the ends of boiler tubes or flues, and to prevent the blowing out of said closure means under the conditions of actual use.

My invention consists in constructing a 15 boiler-plug in the form of a cup shaped disk, the walls of which are concaved or taper outwardly for the purpose of permitting the plug to be readily introduced within a boiler tube normally of a slightly smaller interior 20 diameter than the largest exterior diameter of the plug.

My invention further consists in the improvements and novel arrangement of parts more particularly hereinafter pointed out 25 and claimed.

Attention is hereby directed to the drawing in which similar numerals of designation refer to similar parts throughout the several views.

80 Figure 1 is a horizontal section of my improved plug after it has been duly installed, showing the boiler tube partly in section and partly in elevation. Fig. 2 is a section similar to Fig. 1, but showing in an exaggerated 85 form, for the purposes of illustration, the annular groove in the wall of the plug before it has been expanded into the position shown in Fig. 1.

Referring to the drawing; the plug 3 is 90 composed of metal, and may be rolled, turned, cut, or cast in the form here shown. In the wall 4 of the plug is an annular recess 5, which is extremely shallow, and is preferably concave. My primary purpose 95 in having this recess is to prevent any portion of the wall 4 from coming in contact with the boiler tube while plug is being installed except the portions 6 and 7, which when both are at the same temperature are 100 slightly greater in diameter than the interior diameter of the boiler tube 8. Preferably this difference in diameter is the exact depth of the recess 5.

I prefer to introduce my plug while cold 105 55 into the end of the boiler tube 8 while the same is hot, preferably while it is still under

the influence of the steam of the boiler while in use in order that when my plug expands with the heat, the walls of the plug and tube will come into close contact and the recess 5 60 will be eliminated as shown in Fig. 1. To accomplish this result, it is necessary that the annular recess be of merely sufficient depth to just prevent the said walls from touching,—a microscopic variation being all 65 that is necessary or desirable. Such proportions are not readily observable with the naked eye, and would exist within the width of the line of separation of the walls shown in Fig. 1; the exaggerated recess 5 shown 70 in Fig. 2 for the purposes of illustration not being desirable in my preferred form of construction, though within the scope of my invention. This method of construction differs essentially from "shrinking", as the 75 term is commonly used, since the plug is designed to be introduced not only when the boiler is being made but also after the same has been put into actual use; the heat produced by the boiler being sufficient for causing 80 the walls of my plug and tube to come in contact upon the expanding of the material of which the plug is composed.

In some cases it may be found convenient to construct my plug tapering outwardly, 85 that is, with the diameter of the plug becoming gradually smaller away from the portion 3. But in such case care should be taken to have the taper of the same microscopic dimensions as that of the annular recess 5 above described in order that the walls 90 may just clear when the plug is first installed in position. Since it is my purpose in the preferred form of my invention merely to have sufficient of the surface of the plug to 95 come in contact with the tube in order that the two may be wedged together without splitting the tube, and to have all other parts of the wall of the plug separated in the slightest degree from the wall of the tube 100 while installation is taking place, I desire to include as within my invention any form of plug embodying these features no matter how the recesses are formed or situated.

Through the use of my improved construction, I am able at an instant's notice to install one of my plugs in any boiler tube even where an old form of plug has been used. In the construction now on the market it is common practice to use plugs which are cast 105 solid and driven into the tube without expanding. Such a method of connection is 110

objectionable for the reason that it is hard to make a tight joint and is liable to blow out. Since my plugs are all made in standard sizes with expansion metal they may be 5 rolled or expanded with a tool of the same style as is used to roll or expand the tubes and thus form a greater diameter back of the boiler head by outward pressure on the tube; it would then be impossible with very 10 high hydraulic pressure to start these plugs out. In fact when a new tube is to be installed it is necessary to drill or cut them out, they are held so firmly.

What I claim and desire to secure by Letters Patent is—

- 15 1. The method herein described of plugging the ends of cylindrical boiler tubes consisting in inserting the plug while cold into the tube while the tube is expanded by heat 20 and keeping the tube heated until the plug has become heated to the same temperature as the tube, the plug having a plurality of diameters, the inner one of which when cold fits the bore of the heated tube with a wedging 25 fit and the outer end of which when cold is minutely smaller than the bore of the heated tube, whereby when it thus becomes heated to a temperature equal to that of the tube it will have become expanded sufficiently 30 to cause it to become permanently locked in the tube and have a continuous contact with the inner face of the tube throughout its outer or peripheral surface.
- 35 2. The method herein described of plugging the ends of boiler tubes consisting in inserting the plug while cold into the tube while the tube is expanded by heat and keeping the tube heated until the plug has be-

come heated to the same temperature as the tube, the diameter of the plug at its inner 40 end being such that when thus inserted in a cold state it will have a wedging fit in the bore of the heated tube while the diameter of the plug throughout the larger part of its length is minutely less than the interior 45 diameter of the tube, whereby when it thus becomes heated to a temperature equal to that of the tube it will have become expanded sufficiently to cause it to become permanently locked in the tube and have a continuous contact with the inner face of the tube throughout its outer or peripheral surface.

3. The method herein described of plugging the ends of cylindrical boiler tubes consisting in inserting a hollow plug while cold into the tube while the tube is expanded by heat and keeping the tube heated until the plug has become heated to the same temperature as the tube, the diameter of the 55 plug at its outer and inner ends being such that when it thus becomes heated to a temperature equal to that of the tube said outer and inner ends will have become expanded sufficiently to cause it to become permanently 60 locked in the tube, and the diameter of the plug intermediate said ends being minutely less than at said ends.

In testimony whereof I have hereunto set my hand in presence of two subscribing witnesses, this 30th day of March, 1911.

EUGENE J. McCARTY.
